UNITED STATES PATENT OFFICE.

WALTER T. MAHIN, OF HARRISBURG, PENNSYLVANIA.

SHOE-BLACKING STAND.

1,085,278.

Specification of Letters Patent.

Patented Jan. 27, 1914.

Application filed February 12, 1913. Serial No. 748,040.

To all whom it may concern:

Be it known that I, WALTER T. MAHIN, a citizen of the United States of America, and resident of Harrisburg, in the county of 5 Dauphin and State of Pennsylvania, have invented certain new and useful Improvements in Shoe-Blacking Stands, of which the following is a specification.

This invention relates to shoe blacking stands and has for its object the provision of novel means for retaining a shoe in position to be shined, the said means comprising clamping members adapted to partially embrace the edges of the sole of the shoe 15 under the instep in order that there will be no obstruction to the free movement of the implement used in cleaning and shining the shoes.

A further object of this invention is to 20 provide novel means for operating pairs of clamps which are designed to engage the sole at different points longitudinally of the sole, thus preventing lateral movement of the shoe or any twisting of the shoe with 25 relation to the support, a further object of the invention residing in the provision of means for operating the pairs of clamping members in unison and permitting the 30 equalization of the pressure or clamping action of each pair, notwithstanding that they are operated from a single lever.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this specification 40 wherein like characters denote corresponding parts in the several views, and in which—

Figure 1 illustrates a view in perspective showing a stand embodying the invention; Fig. 2 illustrates a view in side elevation of the upper portion of the said stand; Fig. 3 illustrates a top plan view; Fig. 4 illustrates an enlarged detail plan view underneath the foot support, the means for 45 connecting the foot support to the standard being shown in section; Fig. 5 illustrates a view of the parts shown in Fig. 4 in a different position of adjustment; and Fig. 6 illustrates a vertical sectional view of 50 the foot support and the clamp operating

mechanism, looking from the front, the lever being partly in section.

In these drawings 7 denotes a base plate, 8 a standard, and 9 a companion standard. The standards 8 and 9 have their lower ends 60 bent at angles to form the feet 10 and 11 respectively which are secured to the base 7 by the fastenings 12, which may be of any appropriate type. The standards 8 and 9 are separated at the base but converge and 65 have parallel portions 13 and 14 respectively in contact and secured together by the fastening 15. The standard 9 has an extension 16 which is connected to the plate 17 forming the foot support whereas the standard 70 8 has its upper end supporting a yoke 18 provided with angularly disposed ends 19 secured to the plate 17 by devices 20 which may be in the form of rivets or other appropriate means. The extension 16 of 75 the standard 9 is provided with a bolt 21 by which it is connected to the plate 17.

The slotted bar 22 is supported under the plate 17 in spaced relation therewith, the said slotted bar being held by the bolt 21 80 and by a rivet or like fastening device 23 by which it is held rigid with relation to the plate 17. The slotted member 22 is here shown as having two slots 24 and 25, each of which extends longitudinally of the said 85 bar and the slots are provided for the purpose of permitting movement of the pins 26 and 27 to which the clamps are connected, it being observed that the pin 26 is confined in the slot 24 and the pin 27 travels in the 90 slot 25.

The pairs of clamps consist of the clamping members 28 for one pair of the clamps and the clamping members 29 for another pair of clamps. The clamping members are 95 similar if not identical in construction, each constituting a curved plate, the clamping members 28 having longitudinally extending slots 30 and the members 29 having similar slots 31. The clamping members 100 of each pair are oppositely curved as shown in the drawing and are pivoted on the pins 26 and 27. Guiding lugs 32 are provided for the clamps 29, the said lugs extending from the under surface of the plate 17 105 through the slots 30 and 31 respectively, so that the clamping members are guided by the lugs, and owing to the curved formation of the clamping members and the curved slots therein, the clamping members are ac- 110

tuated laterally of the plate 17 when the means for actuating the clamping members (to be presently explained) is operated. Each clamping member 28 has a lug 34 and 5 each clamping member 29 has a lug 35, the said lugs 34 and 35 being preferably slightly curved to partially embrace the edge of the sole of a shoe so as to prevent vertical movement of the shoe when the clamps are operated to hold the same.

As a means for actuating the clamps in the manner heretofore stated, to produce an equalization of the pressure of each pair of clamps, the pin 26 has a link 36 connected 15 to it and the pin 27 has a link 37 connected to it. The ends of the links remote from the clamps are pivoted to opposite ends of a rocking bar 38 by the pins 39 and 40 respectively, it being shown in Fig. 1 that 20 the end of the rocking bar 38 is provided with a slot 41 for the reception of the link, it being understood that the opposite end of the said rocking bar is likewise provided with a slot (not shown) for the reception of 25 the opposite link.

The rocking bar is rockably mounted at its longitudinal center in a lever 42 which lever terminates in a head 43, the edge or periphery of which is provided with notches forming the teeth 44 adapted to be engaged by a 30 detent, to be presently explained, whereby the lever is held in different positions of adjustment. Brackets 45 depend from the lower surface of the plate 17 and each has an 35 aperture 46 for the pivot 47 on which the lever 42 is mounted so that by swinging the lever 42 on its pivot, the links 36 and 37 which are connected to the rock bar 38 are reciprocated, thus communicating motion to 40 the clamping members and operating them in the manner stated.

The fastener 23 which holds the slotted bar 22, serves as an anchor for a rod 47 which extends forwardly from its point of 45 anchorage and into and through the head of the detent 48 which engages the teeth on the head 43 of the lever for holding the lever at different positions of adjustment. There is a spring 49 encircling the rod 47 interposed 50 between the detent head and the end of the slotted bar 22, the said spring being operative to force the detent into engagement with the ratchet teeth. The detent 48 is formed integral with a plate 50, the said 55 plate being guided between the brackets 45 and having a slot 51 therein for the reception of a screw 52 provided as a further means for guiding the said plate. The end of the plate remote from the ratchet is bent 60 at an angle to form a lug 53 which may be pressed by the operator against the action of the spring 49 for disengaging the detent from the teeth.

It will be apparent that an operator, may, 65 when the clamps are in the position shown

in Fig. 4, pull the lever to cause the clamps to move toward the positions which they are shown to assume in Fig. 5, and the said clamps will travel to such a distance as will cause them to engage the edges of the sole of the shoe which occupy the upper surfaces of 70 the plate, it being understood that regardless of the action of one pair of clamps, the other pair will be caused to engage the sole of the shoe with pressure equal to that of 75 the other pair. When the lever has been operated to produce the required action of the clamps, it is held in position to which it is drawn by the detent or ratchet, and when it is necessary or desirable to release the shoe 80 which has heretofore been clamped, pressure on the outer end of the plate 50 will result in disengaging the detent from the ratchet teeth, permitting the retraction of the lever and the release of the clamps. The relation of the lever to the means for operating 85 the detent is such that both may be conveniently manipulated by one hand.

Owing to the fact that the plate for supporting the shoe is without means for supporting the heel of the shoe, the said heel extends down past the end of the plate and is adapted to bear against the end of the plate so that the edge of the sole is in position to be clamped by the clamping members. A plate of this character, which permits the heel to extend below the surface of the plate insures proper stretching of the leather or shoe material so that the surface 90 may be evenly treated. It is well known 95 that where the heel is supported on the plane of the sole, the shoes crease above the heel and interfere with effective polishing. Furthermore, the fact that the clamps engage the sole under the instep provides for the 100 clamping of soles of different widths and owing to the fact that at this point the soles of all shoes are practically uniform one set of clamps will answer for any of the different shoes.

I claim—

1. In a blacking stand, a support, a plate attached thereto, a slotted bar secured in the plate and spaced therefrom, oppositely curved clamping members forming pairs of 115 clamps, said clamping members having longitudinally disposed slots, pivots connecting the inner ends of each pair of clamps each of the pivots being slidable in a slotted portion of the slotted bar, guiding lugs carried by the plate and extending into the slots of the clamps, links connected to the pivots of the clamps, a rocking bar to the opposite ends of which the links are connected, a pivotally mounted lever in which the rocking bar is rockably mounted, and means for holding the lever in different positions of 120 adjustment.

2. In a blacking stand, a plate, a support therefor, a slotted bar supported by the plate 130

and spaced therefrom, oppositely curved clamping members arranged in pairs and provided with slots, lugs depending from the under surface of the plate and extending 5 through the slots of the clamping members, pivots slidable in the slotted bar on which the pairs of clamping members are mounted, links connected to the pivots, a rock bar, a lever in which the rocking bar is oscillat- 10 ingly mounted and to which the opposite ends of the links are pivoted, teeth formed on a portion of the lever, a detent for holding the lever in different positions of ad-

justment, a guiding bar extending longitudinally of the plate, said detent having an 15 aperture to receive the guiding bar, and a spring interposed between the detent and the guiding bar for holding the detent in engagement with the teeth of the lever.

In testimony whereof, I hereunto affix my 20 signature in the presence of two witnesses.

WALTER T. MAHIN.
